UNITED STATES PATENT OFFICE.

RUSSELL L. DAILEY, OF KANSAS CITY, KANSAS.

OIL-BURNER.

1,077,678.

Specification of Letters Patent. Patented Nov. 4, 1913.

Application filed July 29, 1912, Serial No. 712,167. Renewed September 18, 1913. Serial No. 790,571.

To all whom it may concern:

Be it known that I, RUSSELL L. DAILEY, a citizen of the United States, residing at Kansas City, in the county of Wyandotte 5 and State of Kansas, have invented certain new and useful Improvements in Oil-Burners, of which the following is a specification.

This invention relates to oil burners, of that class wherein steam, under pressure, is utilized to atomize and partially oxygenize 10 oil for the purpose of producing a combustible gas, and my object is to produce a burner of the character outlined which can be used in cooking stoves or in heating stoves or furnaces.

A further object is to produce an efficient burner of this character by which combustion can be regulated and controlled.

With these and other objects in view, the 20 invention consists in certain novel and peculiar features of construction and organization as hereinafter described and claimed; and in order that it may be clearly understood, reference is to be had to the accompanying drawings, in which:—

Figure 1, is a top plan view of a burner embodying my invention. Fig. 2, is a vertical section on the line II—II of Fig. 1. Fig. 3, is a horizontal section on the line 30 III—III of Fig. 2. Fig. 4, is a vertical section on the line IV—IV of Fig. 2. Fig. 5, is a vertical section on the line V—V of Fig. 2. Fig. 6, is a fragmentary side view of the burner.

In the said drawings, 1 is a base plate or shallow pan adapted in practice, to serve as a horizontal partition for the combustion chamber of stove or furnace, from which by preference, the grate has been removed, 40 and said plate or pan is provided centrally with a depressed perforated portion 2, through which air may pass upward to support combustion, as hereinafter explained, and around said depressed portion the pan 45 is provided with an interior wall 3, so that oil discharged into said pan cannot escape through the perforated portion thereof.

The depressed portion is provided centrally with an opening 4 and extending 50 justably through said opening is a threaded post 5, clamping nuts 6 serving to secure the post at the desired point of adjustment. Screwed upon and supported by the post is a conical spreader 7, provided at its lower 55 end with a surrounding trough or gutter 8, from which oil may overflow into the pan,

and at suitable points the latter is provided with sockets 9 for the reception of the supporting legs 10 of the upper portion of the burner, the same being constructed as follows: 11 is an inverted hollow frustum-shaped receiver open at its lower end and arranged with its axis or longitudinal center in line with the apex of the conical spreader, and said receiver is provided with one or 60 more vertical slots 12, and above said slots with upwardly-projecting perforated lugs 13. Arranged radially with respect to the receiver, is one or more steam receptacles 14, each closed at its inner end by an upright 65 rib 15 fitting snugly in slot 12 of the receiver, and provided with a plurality of jet orifices 16, and each receptacle is provided at its inner end with a flange 17 fitting against the receiver around the slot 12 there- 70 of into which the rib of such receptacle projects, and the upper and lower ends of said flange are bolted at 18 and 19 respectively to a lug 13 of and to the body of the receiver. Each receptacle 14 is divided by a partition 75 80 19^a, into an inner chamber 20 and an outer chamber 21, and said partition is provided with an orifice 22 controlled by an adjustable needle valve 23 extending radially through chamber 21 and adjustably mounted in the outer wall of the receptacle. The 85 receptacles when in place, are disposed at uniform distances apart, and are provided with openings 24 in the upper walls of chambers 21, and at opposite sides of said 90 openings with laterally projecting bifurcated lugs 25. Arranged horizontally above the said receptacle or receptacles, is a steam ring 26, provided vertically above each chamber 21, with a depending nipple 27 95 which fits in the adjacent opening 24, and said nipples above the receptacles, are enlarged at 28, to provide downwardly-facing shoulders 29, between which and the receptacles, gaskets 30 are fitted to make the 100 joints between the nipples and the receptacles steam-tight, the said nipples having threaded sockets 31, to receive the threaded ends of clamping bolts 32, extending up through said bifurcated lugs 25, for the purpose of securing the receptacles firmly to the ring 26.

Corresponding in number and arranged alternately with respect to the receptacles 14, is a series of upright steam generators 110 33, the lower ends of the same lying in substantially the same plane as the bottom of

the receiver, and their upper ends projecting to a considerable height above the receiver, and through the space inclosed by said ring, and below said ring said generators 5 are provided with outwardly-projecting or step portions 34, underlying the ring. The top of said step portions are provided with openings 35 receiving nipples 36 depending from the ring, and said nipples are 10 enlarged to provide downwardly-facing shoulders 37 whereby to clamp gaskets 38 upon the said tops of the step portions, and projecting from opposite sides of said tops are bifurcated lugs 39 through which bolts 15 extend upward into threaded sockets 41 in the enlargement of said nipples, to clamp the ring and the generators firmly together, and for the support of said ring, the generators are mounted upon the legs 10, herein 20 before described.

The generators are provided with partitions 42 depending from the inner ends of the tops of the step portions, and inward of said partitions, the generators are provided 25 with alternately arranged oppositely-projecting baffle plates 43 and 44 whereby the interior of the generators, inward of the step portions is converted into tortuous passages which communicate at their lower 30 ends, with the spaces or chambers outward of partitions 42.

At their extreme upper ends the generators are provided centrally with openings 45, and laterally-projecting bifurcated lugs 46, 35 and arranged above the generators and concentrically with respect to the receiver, is a circular water chamber 47 provided with depending nipples 48 fitting in the openings 45, and interposed between the upper 40 ends of the generators and said water chamber are gaskets 49 to establish steam-tight joints between the generators and the water receptacles, bolts 50 extending up through the bifurcated lugs 46, and into sockets 51 45 in the bottom of the water receptacle, to clamp the same firmly to the generators, and to control the volume of water passing from the water receptacle through said nipples into the generators, needle valves 52 are provided, the same extending through the top 50 of the water receptacle and into said nipples, as shown.

53 is a water supply pipe communicating with the water receptacle and adapted to be 55 provided with the customary valve, not shown, and with a check valve, not shown, to prevent steam backing up through the water pipe unless the steam attains an excessive pressure.

60 54 is an oil supply pipe, provided with a suitable controlling valve, not shown, and extending downward into the receiver 11 in vertical alinement with the apex of the conical spreader 7, and said oil supply pipe 65 is enlarged above the water receptacle by

the use of a T-coupling 55. Extending into said coupling through the stem thereof, is a steam pipe 56, communicating at its lower end with the steam ring 26, and depending from the upper end of the steam pipe is a steam nozzle 57 to act as an injector to drive the oil supplied by pipe 54, into the receiver with considerable force. 70

Assuming the burner shown and described, is in position in a stove or furnace, oil is 75 permitted to flow through the supply pipe into the base or pan, the oil upon its discharge from the pipe falling upon the spreader and overflowing from the trough or gutter thereof into the pan, or oil may be 80 otherwise supplied to the pan. If the pan is charged with oil from the supply pipe, the latter is closed when the pan contains the required quantity of oil. The oil in the pan is ignited by means of a torch not 85 shown, and in burning highly heats the spreader and the other parts of the burner overlying the pan. When the temperature of the burner is thus raised sufficiently, oil is permitted to flow through pipe 54, and at the same time water is supplied through pipe 53 to the water receptacle 47, and from said receptacle, the water passes through the nipples 48 into the generators and travels downwardly therein from baffle plate to 90 baffle plate in a tortuous course, and is converted into steam in said generators, the steam passing upwardly from the same through nipples 36 into the steam ring 26, and from the steam ring it passes downward through nipples 27 into chambers 21 of the steam receptacles, and thence passes inwardly through the valve-controlled openings 22 into the nozzle chambers 20, and is discharged radially inward therefrom 95 through the jet orifices 16, into the receiver, it being understood that the steam generated in the generators is superheated in its passage from the ring, into the receiver through said orifices 16, and in passing from chambers 21 into chambers 20, its pressure is reduced. As a result of this reduction of 100 pressure and the discharge through a plurality of orifices into the receiver, the burner 105 will operate with but little noise. 110

The forcible discharge of the steam into the receiver in numerous jets results in the 115 complete atomization of the oil falling from pipe 54 through the receiver upon the spreader, and such atomized oil, thoroughly 120 mixed with steam, passes out of the receiver and in a downwardly and outwardly direction around the spreader, and then starts upward, being immediately mixed with air which passes upward through the perforated portion of the pan. This mixture of 125 atomized oil and air produces a highly combustible gas which is immediately ignited from the flame of the burning oil in the pan, the flames from the burning gas reach- 130

ing upward and completely enveloping that portion of the burner above and surrounding the receiver and following the direction indicated by the featherless arrows on Fig. 2.

5 The atomization of the oil is made more thorough by the use of the steam pipe 56 connected to the ring at one end, and provided with a nozzle at its opposite end for giving an injecting action on the oil, as the forcible downward discharge of steam in the lower end of the oil supply pipe tends to disrupt and spread and therefore atomize the oil in its passage from said nozzle to the receiver, and thus renders the action of the 10 jets of steam from orifices 16 more effective than would be the case if the injecting action of the steam was dispensed with.

15 It will be understood that the amount of oil and water permitted to enter the burner 20 will determine the volume of heat produced. The amount of water permitted to enter the generators may be controlled entirely by the needle valves 52. The pressure of the steam can be regulated by the adjustment of 25 valves 23. The quantity of oil will be regulated by the customary valve in pipe 54, hereinbefore referred to.

30 From the above description it will be apparent that I have produced an oil burner embodying the features of advantage enumerated as desirable in the statement of the object of the invention, and while I have illustrated the preferred embodiment of the invention, it is to be understood that it may 35 be modified in form, proportion, detail construction and organization without departing from the principle of construction as defined in the appended claims.

I claim:

40 1. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, and an oil supply pipe for dis- 45 charging oil into the receiver so that it shall fall upon the spreader and in its passage thereto be intercepted by the steam from said jet orifice or orifices.

55 2. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, an oil supply pipe for dis- 60 charging oil into the receiver so that it shall fall upon the spreader and in its pas- 65

sage thereto be intercepted by the steam from said jet orifice or orifices, and means for controlling the passage of steam from the generator or generators to the receptacle or receptacles.

70 3. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, an oil supply pipe for dis- 75 charging oil into the receiver so that it shall fall upon the spreader and in its passage thereto be intercepted by the steam from said jet orifice or orifices, and an adjustable valve in each receptacle for controlling the 80 volume of steam passing from the generator or generators to the said jet orifice or orifices.

85 4. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, an oil supply pipe for dis- 90 charging oil into the receiver so that it shall fall upon the spreader and in its passage thereto be intercepted by the steam from said jet orifice or orifices, and a steam supply pipe to receive steam from the generator or generators and discharge it into the oil supply pipe toward the discharge end 95 thereof.

100 5. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, an oil supply pipe for dis- 110 charging oil into the receiver so that it shall fall upon the spreader and in its passage thereto be intercepted by the steam from said jet orifice or orifices, means for controlling the passage of steam from the generator or generators to the receptacle or receptacles, and a steam supply pipe to receive steam from the generator or generators and discharge it into the oil supply pipe toward the discharge end 115 thereof.

120 6. An oil burner, comprising an apertured base plate, a spreader above the apertured portion of the plate, a downwardly-opening receiver above the spreader, one or more steam generators adjacent to the re- 125

ceiver, one or more steam receptacles to receive steam produced in the generator or generators and each provided with one or more jet orifices to discharge steam radially into the receiver, a steam ring connected to the generator or generators and to said steam receptacle or receptacles to conduct steam from the former to the latter, and an oil supply pipe for discharging oil into the receiver so that it shall fall upon the spreader and in its passage thereto be intercepted by the steam from said jet orifice or orifices.

7. An oil burner, comprising an apertured base plate, a spreader above the apertured portion of the plate, a downwardly-opening receiver above the spreader, one or more steam generators adjacent to the receiver, one or more steam receptacles to receive steam produced in the generator or generators and each provided with one or more jet orifices to discharge steam radially into the receiver, a water receptacle resting upon and communicating with the generator or generators, a valve or valves controlling the passage of water from said receptacle into said generator or generators, and an oil supply pipe for discharging oil into the receiver so that it shall fall upon the spreader and in its passage thereto be intercepted by the steam from said jet orifice or orifices.

8. An oil burner, comprising an apertured plate, a spreader supported above the plate, a downwardly-opening receiver above the spreader, a plurality of steam generators arranged around the receiver and above the plate, a circular water receptacle resting upon and communicating with the upper ends of said generators, valves controlling the passage of water from the receptacle into the generators, a plurality of radially arranged steam receptacles arranged around the receiver and between adjacent generators and adapted to discharge jets of steam radially into the receiver, valves controlling the passage of steam through said steam receptacles, a steam ring above said receptacles and communicating therewith and with the generators to receive steam from the latter and discharge it into the former outward of the valves thereof, and an oil supply pipe extending down through the space inclosed by the water receptacle and steam ring and into the upper end of the said receiver.

9. An oil burner, comprising an apertured plate, a spreader supported above the plate, a downwardly-opening receiver above the spreader, a plurality of steam generators arranged around the receiver and above the plate, a circular water receptacle resting upon and communicating with the upper ends of said generators, valves controlling the passage of water from the receptacle into the generators, a plurality of radially arranged

steam receptacles arranged around the receiver and between adjacent generators and adapted to discharge jets of steam radially into the receiver, valves controlling the passage of steam through said steam receptacles, a steam ring above said receptacles and communicating therewith and with the generators to receive steam from the latter and discharge it into the former outward of the valves thereof, an oil supply pipe extending down through the space inclosed by the water receptacle and steam ring and into the upper end of the said receiver, and a pipe extending upward from the steam ring into the oil supply pipe and provided with a nozzle extending downward in the supply pipe, toward the receiver.

10. In an oil burner, an oil feed and a steam chamber with one or more communicating passages therebetween, a steam generator provided with a step portion supporting said steam chamber and divided into two compartments communicating at the lower end of the step portion, a discharge opening from one of said compartments into the steam chamber, and the other compartment having a receiving opening and provided with a plurality of baffle plates forming a tortuous passage.

11. A steam receptacle for oil burners, provided with a perforated partition dividing it into two chambers, and provided at the inner end of one chamber with one or more jet orifices, and an adjustable valve extending through the outer wall of the other chamber and into the perforation of said partition to control the passage of steam therethrough from the outer chamber into the inner chamber; said receptacle also having a receiving opening communicating with its outer chamber.

12. In an oil burner, a downwardly-opening receiver provided with one or more vertical slots and one or more upwardly-projecting lugs, and a corresponding number of steam receptacles arranged radially of said receiver, and each provided with an orificed rib projecting into one of the slots of the receiver, and with a flange surrounding the said slots and bearing against the receiver, bolts extending through the flange of each receptacle, certain of the bolts extending into the receiver, and others through the upwardly-projecting lugs thereof, and a conical spreader arranged vertically under the receiver and provided with a surrounding trough or gutter.

In testimony whereof I affix my signature, in the presence of two witnesses.

RUSSELL L. DAILEY.
